**COMBINED ILLUMINABLE TRANSPARENT
FLOWER AND AQUARIUM STAND**

Lloyd Russ, New York, N. Y.

Application July 16, 1956, Serial No. 42,254

Term of patent 14 years

(Cl. D91—2)

FIG. 1.

FIG. 2.

FIG. 3.

FIG. 5.

FIG. 4.

Fig. 1 is a top plan view of the combined illuminable transparent flower and aquarium stand showing my new design,

Fig. 2 is a front elevation of the design shown in Fig. 1,

Fig. 3 is a rear elevational view thereof,

Fig. 4 is an end elevational view, and

Fig. 5 is a perspective view thereof.

The broken lines shown in Figs. 1, 2 and 5 are for illustrative purposes only.

Both ends of the combined illuminable transparent flower and aquarium stand are the same in detail as that shown in Fig. 4.

I claim:

The ornamental design for a combined illuminable transparent flower and aquarium stand, as shown and described.
